UNITED STATES PATENT OFFICE.

ELMER A. BRECKENFELD, OF BERKELEY, CALIFORNIA, ASSIGNOR TO RAND COMPANY, INC., OF NORTH TONAWANDA, NEW YORK, A CORPORATION OF NEW YORK.

INDEX HOLDER.

Application filed June 30, 1924. Serial No. 723,169.

In the sale of inks, paints and the like it is frequently desirable to display the different colors in compact and accessible form and in such manner that certain colors may 5 be readily added or withdrawn or substituted without detracting from the general appearance of the display. For this purpose visible indexes of the type having overlapping cards with their margins exposed 10 would be admirably adapted, the color cards being inserted in the pockets formed by the celluloid sheaths with which such card holders are ordinarily provided, if it were not for the fact that the celluloid sheaths, 15 while apparently transparent, filter out certain components of color and change the apparent hue of the color cards.

The object of the present invention is to provide holders for cards and the like which 20 have the usual desirable characteristics of visible indexes and which at the same time will display colors or other subject-matter without distortion.

For the purpose of illustration one concrete embodiment of the invention is illustrated in the accompanying drawings in which:—

Fig. 1 is a front view of a typical card holder adapted to the aforesaid end; and 30 Fig. 2 is an enlarged sectional view on the line 2—2 of Fig. 1.

The particular embodiment of the invention chosen for the purpose of illustration comprises a card C joined to a rail R by means of a fabric strip F and a celluloid sheath S folded over the lower margin of the card and secured thereto by staples P. The rail R projects beyond the sides of the card so that the ends may be inserted under the overlapping flanges of a visible index holder, the rails of adjacent cards fitting closely together with the cards attached thereto overlapping each other in the usual manner. The fabric strip S provides a

hinged connection between the card and rail 45 so that the cards may be swung upwardly to inspect underlying cards without removing the rails from the holders. The card K, which carries the index material, is preferably mounted by inserting its lower margin between the sheath S and the back C and inserting the upper corners through slits T in the back C. The sheath S is preferably made of translucent celluloid having its forward edge folded under as shown at 50 E in Fig. 2 to facilitate the insertion of the card K.

According to the present invention the sheath S is provided with a window W through which the card K is displayed without lifting the superposed cards. In the case of color cards the margin of the inserted card may be colored as indicated by the stippling in Fig. 1 and the body of the card may carry the indicia indicating the 65 number of the particular color and the company producing the ink or paint represented by the card. By virtue of the window W the true color of the card may be determined without lifting the superposed cards, thereby avoiding the confusion and inaccuracy which would result in attempting to ascertain the true color by looking through the translucent celluloid sheath.

I claim:

A card index holder of the type adapted to be mounted in overlapping relationship with other holders, with the margin thereof exposed, a celluloid sheath over said margin to provide a pocket, and a card in said holder having a colored margin within said pocket, said sheath having a window intermediate the ends of said card permitting display of the true color of said card margin therethrough.

Signed by me at San Francisco, California, this nineteenth day of June, 1924.

E. A. BRECKENFELD.
